UNITED STATES PATENT OFFICE.

MAX LEVIN, OF CHICAGO, ILLINOIS.

MANURE-BOX.

1,327,397.

Specification of Letters Patent. Patented Jan. 6, 1920.

Application filed March 22, 1915. Serial No. 16,241.

To all whom it may concern:

Be it known that I, MAX LEVIN, a resident of Chicago, in the county of Cook and State of Illinois, have invented certain new and 5 useful Improvements in Manure-Boxes, of which the following is a full, clear, and exact description.

The invention relates to manure boxes.

One object of the invention is to provide 10 an improved box, particularly adapted to receive and contain manure, until such time as it may be desired to remove the same.

Another object of the invention is to provide 15 a box of this character which is sanitary and in which the material will be retained.

Another object of the invention is to provide 20 an improved metallic box for this purpose, which is adapted to be conveniently moved out of a barn when its contents are to be removed and returned after such removal.

The invention consists in the several novel 25 features hereinafter set forth and more particularly defined by a claim at the conclusion hereof.

In the drawings: Figure 1 is a perspective of a box embodying the invention, the 30 cover being shown partly open. Fig. 2 is a vertical longitudinal section. Fig. 3 is a vertical transverse section.

The body of the box comprises a bottom 35 5, ends 6 and 7, a back 8 and a front 9, all of which are formed of sheet metal. The top of this body is open and is adapted to be closed by a cover 10 fitting over the open top of the body. This cover is connected to the back by hinges 11^a so that the cover may be conveniently lifted when material is to 40 be placed in the box. The box body is supported at each corner by an angle iron post 11 the lower portions of which form legs for supporting the body above the floor.

The central portion of the box is bound 45 by a metal strip 12 which is secured to the front, back and bottom of the box body to render the central portion of the box more rigid. Braces 14 are secured to the corner legs and to the box bottom to render the 50 bottom rigid. A caster 15 is provided at the lower end of each post 11, so that the box may be wheeled around from place to place. Each caster is provided with a bolt 16 extending through an inturned terminal 55 17 upon the post and secured thereto by a nut 18, it being understood that the casters

are free to swivel, as well understood in the art. Cross bar 19 has its front and rear terminals bent laterally and secured to the front and back respectively of the box body 60 to prevent the central portion of the box from spreading by the load in the box. The upper edge of the front, end and back walls of the box body are reinforced by an angle iron bar 20. The vertical flange of this reinforcing bar is secured to the walls of the box body, the upper edge of the metal forming such walls being lapped around the upper edge of said flange, as at 21. The other flange 22 of the reinforcing bar is disposed 65 below the upper edge of the box. A disinfectant container 23, consisting of a semi-cylindrical perforated shell and end flanges 24 is slidably held in guide strips 25 secured to the end wall 6 of the box. This 70 shell is adapted to contain the absorbent material 26 which may be saturated with a disinfectant from time to time. By removing the container, access is afforded to recharge it when the disinfectant becomes 75 spent.

The cover 10 is also made of sheet metal and at the front and ends thereof this sheet metal is flanged downwardly, as at 28, to extend around the reinforcing bar 20. The 80 flanged portions of the cover are reinforced by a bar 29 which is secured thereto. To strengthen the central portion of the cover, a bar 30 is secured to the top thereof and the front terminal is extended, as at 31, 85 to form a grip or handle whereby the cover can be conveniently raised and lowered. A guard strip 33 is secured to the cover within and adjacent the back wall of the box to prevent material from being caught 90 between the cover and the rear of the box body when the box is being loaded, so that the material will not prevent the cover from being properly closed.

A loop 34 is pivotally connected to each 100 box end by a strip 35 and these loops serve as handles for convenience in shifting the box from place to place.

In practice, the material is thrust into the box body when the cover is raised. To provide for the convenient removal of the contents without lifting the same out of the box, a door 36 adapted to close an opening 37 in one end of the box, is connected to the 105 box body by hinges 38 which are secured 110 to the bottom of the box. Keepers 39, which are pivoted, as at 40, to a bar 41 se-

cured to the end of the box, are provided to hold the door 36 normally closed. This door is formed of a piece of sheet metal 42 with a metallic binding strip 43 secured to its margin on the outer side thereof. The door is extended to a point below the bottom of the box body to form an extension 44 adapted to extend under the box bottom when the door is open, and to hold the door 10 in downwardly inclined position, as indicated by dotted lines in Fig. 2. This extension also prevents the material from passing where it will interfere with the closing of the door. A handle 45 is secured to the 15 door.

In practice, it has been found desirable to provide an improved manure box which is sanitary and which may be conveniently kept in the barn to receive material when 20 desired, and which, when it is to be emptied, can be conveniently wheeled out of the barn for the removal of the contents from the box. The invention is particularly designed to meet this condition, being provided with wheels for facilitating its movement from place to place and being constructed so that its contents will be closely 25 confined. The invention exemplifies a box all portions of which are metallic and re-

inforced to render it durable. The opening in the box at one side thereof and adjacent the bottom makes it possible to easily remove the material from the box without lifting it through the open top. 30

The invention is not to be understood as restricted to the details set forth, since these may be modified within the scope of the appended claim without departing from the spirit and scope of the invention. 35

Having thus described my invention, what 40 I claim as new, and desire to secure by Letters Patent, is:—

A manure box comprising a body having a bottom, front, back and sides and its top open, a cover hinged to the body to permit material to be discharged into the body through the open top, said body having an opening in one side thereof adjacent the bottom, and a door hinged to the bottom of the body to swing downwardly and outwardly for closing said opening, said door being provided with an extension disposed to swing under the bottom when the door is open. 45 50
